UNITED STATES PATENT OFFICE

2,668,517

HYDRAULIC OIL WELL PUMP JACK

Chester R. Craft, St. Louis, Mo.

Application October 23, 1951, Serial No. 252,764

3 Claims. (Cl. 121—1)

1

My invention relates to improvements in hydraulic oil well pump jacks and has for one object to provide a new and improved form of hydraulic jack which will be light, portable, durable and shall require a minimum of power to operate.

Another object of the invention is to provide an oil well pump jack wherein the weight of the pump rod will be cushioned in its downward descent and wherein changes in direction up and down of the pump rod and polish rod will be cushioned to prevent vibration.

Another object of the invention is to provide a hydraulic pump jack which can be easily and accurately centered over the well and which can be withdrawn when it is necessary to service the well and thereafter easily and accurately returned to its position.

Among the advantages of my invention are the fact that its construction uses less than half as much steel as is used in other devices for the same purpose and the cost of construction is greatly reduced. There are no bearings, wrist pins, gears, rubbing parts carrying the load of raising the sucker rod. All working parts run in oil. There is a steady pull on the rods. The operation is cushioned and the device may be easily removed when it is necessary to work on the well. Moreover, any length of stroke desired and any stroke speed may be obtained by adjustment of the buttons on the valve rod and by changing the speed of the output of the pump.

Other objects will appear from time to time in the specification and claims.

My invention is illustrated more or less diagrammatically in the accompanying drawings, wherein:

Figure 1 is a side elevation of the jack in place;

Figure 2 is a section taken along the line 2—2 of Figure 1;

Figure 3 is a section with parts omitted along the line 3—3 of Figure 1;

Figure 4 is a section along the line 4—4 of Figure 1;

Figure 5 is a section on an enlarged scale of part of the hydraulic valve control and actuating mechanism;

Figure 6 is a longitudinal section through the pump cylinder; and

Figure 7 is a side elevation on an enlarged scale showing the valves in a different position from that shown in Figure 1.

Like parts are indicated by like characters throughout the specification and drawings.

1 is the casing head of an oil well. 2 is the well tubing extending through the casing head

2

and terminating in a flow T 3. 4 is a bleeder line controlled by a valve 5. 6 is the oil flow line to storage tank. 7 is the pump sucker rod. 8 is the sub-coupling which connects the polish rod 9 to the sucker rod 7.

10 is the stuffing box through which the polish rod extends. It will be understood that at the lower end of the pump sucker rod is the reciprocable pump mechanism down inside the casing 11 and the purpose of the pump jack is to cause the sucker rod and pump mechanism to reciprocate up and down to pump oil out of the well. The hydraulic pump jack works on the polish rod as will hereinafter appear.

12 indicates a concrete foundation, though to be sure, it might be of other material. It might be two parallel walls as indicated, or a rectangular box or any suitable shape or arrangement so that it is rigid and located on both sides of the well. The foundation 12 carries the track 13, on which travel six or more track wheels 14 which support the chassis 15 of the jack mechanism.

In the position shown in Figure 1, the jack is 25 spotted over the well in such position that the jack mechanism may actuate the polish rod and thereby actuate the pump but, if the sucker rod were otherwise supported and the polish rod disconnected from it and drawn out, then the 30 jack and all its associated parts can be rolled back on the tracks 13 to clear the casing so that the well may be serviced.

Resting on the cross pieces 17 on the end of the chassis 15 is the base plate 18. Rising from the base plate is the oil jack cylinder 19. Concentric with the oil jack cylinder 19 is an inner cylinder 20. The base plate 18 is centrally apertured at 21 and the lower ends of the cylinders 19 and 20 are both welded or otherwise permanently attached to the base plate so that the polish rod 9 may extend upwardly clear through and project above the upper end of the oil jack cylinder.

22 is the jack piston. It projects upwardly 45 through the screw cap 23, the screw cap being threaded on the jack cylinder 19 and centrally apertured to permit passage of the jack piston 22. The jack piston includes the sleeve 24 which encircles the tube 20. It is threaded at its lower end as at 25 to engage the annular plunger 26. The annular plunger 26 has packing rings 27 between its outer periphery and the inner periphery of the jack cylinder and inner packing rings 28 between its inner periphery and the 55 outer periphery of the cylinder or sleeve 20. The

upper end of the sleeve or piston rod 24 is enlarged or flanged at 29 to rest upon the screw cap 23 when in its lower position and the enlargement is apertured as at 30 to permit the polish rod 9 to extend therethrough.

31 is a polish rod clamp, tightly but releasably mounted on the polish rod and adapted to engage the upper end of the hollow piston rod or sleeve 24. 32 is a double box coupling threaded on the upper end of the polish rod 9 which may be used to attach a separate tool to raise the polish rod independent of the movement of the piston.

34 is a bleeder outlet controlled by a manual valve 35 communicating with the upper end of the jack cylinder above the plunger 26. 36 is an intake pipe and 37 an exhaust pipe, both communicating with the jack cylinder below the plunger. In view of the fact that the plunger is packed both in its relationship with the jack cylinder 19 and the central sleeve 20, and 19 and 20 are both welded to the base plate 18, if hydraulic fluid is forced in through the high pressure intake hydraulic fluid line 36, and it cannot escape to the outlet hydraulic fluid line 37, the piston will go up, carrying with it the polish rod and so actuating the pump. If, thereafter, the flow is cut off and the oil is allowed to escape through outlet 37, gravity will reverse the movement and cause the pump mechanism to descend.

38 is a housing on the chassis 15. It contains a motor which may be steam or electric or internal combustion as the case may be, diagrammatically indicated at 39. This motor drives a compressor diagrammatically indicated at 40. 41 is an oil or hydraulic fluid reservoir in the chassis 15 beneath the motor and pump housing. The pump may be a reciprocating pump, a centrifugal pump or any other desired type of pump which will generate hydraulic pressure. 42 is a pipe leading from the pump to a T 43. 44 is a pipe extending to the valve housing 45. In this housing is an intake valve 46 and the pipe 47 leads from the housing 45 to the high pressure intake line 36. The pipes, T and valve housings are, of course, connected by couplings in the usual manner.

48 is a pipe leading from the pipe 37 to the valve housing 49. The pipe 50 leads from the exhaust valve housing 49 to the pipe 51 which leads to the reservoir 41. Between the T 43 and the return pipe 52 leading to reservoir 41 is a recirculating valve 53. This is an adjustable pressure control relief valve. It opens when a predetermined pressure has been reached to permit flow from the pump to the reservoir bypassing the hydraulic jack cylinder.

Under ordinary circumstances, hydraulic fluid passes from the pump to the valve housing 45 past the open intake valve 46 into the cylinder and the piston rises. As the piston reaches the end of its stroke, the intake valve is closed and the pump pressure is bled off through the relief or recirculating valve 53. During the upward movement of the piston, the outlet valve 54 in the valve housing 49 is closed but, when the plunger or piston reaches the upper end of its excursion, this valve 54 opens and, since no oil is being fed to the piston, the oil escapes through the outlet valve to the reservoir. The resistance to flow in the circuit including the outlet valve is sufficient to prevent a free fall of the pump sucker rod and polish rod and to cushion the downward movement.

This actuating of the valves is accomplished in the following manner: Extending laterally from the enlarged head 29 of the jack piston 22 is a valve operating rod bracket 55. This bracket supports a valve operating rod 56 which is free to reciprocate in a housing or valve operating guide 57. On this valve operating rod 56 are four control buttons 58, 59, 60 and 61. The valve operating rod guide 57 is slotted adjacent the outlet valve housing 54 and the high pressure valve housing 45. A lever 62, extending from each of these valves, projects into the path of the buttons. As the piston moves up and down, these buttons contact these levers. The levers by any suitable snap action mechanism, of which many are standard in the valve field and the details of which are not here shown, will move each valve from open to closed position or vice versa as the jack operates.

Thus, with the intake valve open and the exhaust valve closed, the pump exerts a pressure to raise the piston or plunger. The plunger goes up, carrying with it the polish rod and also carrying with it the valve operating bracket and the valve operating rod. As the piston approaches the upper end of its stroke, the buttons 58 and 59 on the valve rod 56 close the intake valve and open the exhaust valve respectively. The pump goes right on pumping but now the discharge is bypassed and, since the exhaust valve 54 is open, the weight of the plunger and the string of sucker rods causes downward movement. As the piston approaches the lower end of its excursion, the valves are again operated by the buttons 60 and 61 to close the exhaust and open the intake valve respectively. This happens a short distance before the end of the stroke so that the pump has time to build up pressure to cushion the downward movement and reverse it.

The longitudinal position of the valve rod 56 may be adjusted with respect to the longitudinal position of the plunger 22 by the threaded nuts, as indicated at 62. The buttons 58, 59, 60 and 61 may also be adjustably positioned on the valve stem 56, the particular means for locking the buttons on the valve being not here illustrated as they are conventional and form no part of the present invention. This adjustable arrangement makes it possible to change the length of stroke and also makes it possible to adjust the point at which, during downward movement of the plunger, the cushioning effect is built up so that accurate, smooth operation of the oil well pump jack may be insured.

It will be realized that, whereas I have described and illustrated an operative device, still many changes might be made in the size, shape, number, arrangement and disposition of the parts without departing materially from the spirit of my invention. I wish, therefore, that my showing be taken in a broad sense as diagrammatic and illustrative rather than limiting me to my precise showing.

I claim:

1. In an oil well pump jack including a supporting base, a motor cylinder on the base adapted to be positioned with its axis in alignment with the axis of the well, an annular piston in the cylinder, a sleeve within the cylinder concentric therewith and packing means between outer periphery of the piston and the inner periphery of the cylinder, and between the inner periphery of the piston and the outer periphery of the sleeve, the bottom and top of the cylinder being apertured to permit the polish rod of a well

pump to extend therethrough and project therefrom at both ends, means for supporting the polish rod on the piston above the upper end of the cylinder, hydraulic means for raising the piston.

2. In an oil well pump jack including a supporting base, a motor cylinder on the base adapted to be positioned with its axis in alignment with the axis of the well, an annular piston in the cylinder, a sleeve within the cylinder concentric therewith and packing means between the outer periphery of the piston and the inner periphery of the cylinder, and between the inner periphery of the piston and the outer periphery of the sleeve, the bottom and top of the cylinder being apertured to permit the polish rod of a well pump to extend therethrough and project therefrom at both ends, means for supporting the polish rod on the piston above the upper end of the cylinder, hydraulic means for raising the piston, means associated with the polish rod, above the cylinder for raising the rod independent of the piston.

3. In an oil well pump jack a supporting base, a motor jack cylinder mounted on the base whereby the axis of the cylinder may be aligned

with the axis of a well, a hollow piston and hollow piston rod in the cylinder, a sleeve rigidly mounted in the cylinder within the piston and piston rod whereby there is a clear passage from top to bottom through the cylinder, a polish rod adapted to extend through the cylinder in such clear passage, means for supporting the polish rod on the piston, and separate means independent of the piston whereby the polish rod may be raised and lowered.
